CLAIM

The ornamental design for a tire rim, as shown and described.

DESCRIPTION

FIG. 1 shows a front view of my design for a tire rim; FIG. 2 shows a perspective view of the tire rim shown in FIG. 1;

FIG. 3 shows a front view of a second embodiment of my invention;

FIG. 4 shows a perspective view of the tire rim shown in FIG. 3;

FIG. 5 shows a front view of a third embodiment of my invention; and,

FIG. 6 shows a perspective view of the tire rim shown in FIG. 5.

The broken lines in FIGS. 2, 4, and 6, showing the side of the rim, are for illustrative purposes only and form no part of the claimed invention. The rear of the tire rim is not shown and forms no part of the claimed invention.
